UNITED STATES PATENT OFFICE

GEORGE W. HENRY, JR., AND SAMUEL J. THACKERAY, OF PHILADELPHIA, PENNSYLVANIA, ASSIGNORS TO SOABAR COMPANY, OF PHILADELPHIA, PENNSYLVANIA, A CORPORATION OF PENNSYLVANIA

TICKET AND LABEL PRINTING MACHINE

Application filed December 8, 1928. Serial No. 324,741.

Our invention relates to certain improvements in machines for printing tickets provided with either strings or pins, and for printing upon gummed labels. Such tickets and labels are used on merchandise to indicate style, size, price, etc.

One object of the invention is to provide a simple hand machine for feeding the labels, string-tickets or pin-tickets to the printing position.

10 The invention also relates to certain improvements in the mounting of the type form so that it can be turned at right angles to print either transversely or longitudinally.

15 The invention further relates to certain improvements in the pawls for feeding the tickets and gummed labels to the machine.

In the accompanying drawings:

Fig. 1 is a side view of our improved ticket 20 and label printing machine;

Fig. 2 is an end view;

Fig. 3 is a transverse sectional view on the line 3—3, Fig. 1;

25 Fig. 4 is a transverse section on the line 4—4, Fig. 1;

Fig. 5 is a sectional plan view on the line 5—5, Fig. 1;

Fig. 6 is a detached perspective view of the 30 chase-holder;

Fig. 7 is a perspective view of a portion of a strip of gummed labels;

Fig. 8 is a portion of a strip of pin-tickets;

Fig. 9 is a portion of a strip of string-tickets;

35 Fig. 10 is an inverted plan view of a modification of the chase-holder;

Fig. 11 is a side view of the same; and

Fig. 12 is a sectional view on the line 12—12, Fig. 10.

40 Referring to the drawings, 1 is the base of the machine which is circular in form and arranged to contain a roll of gummed labels, shown by dotted lines in Fig. 1. These gummed labels pass through a slot 2 in the base, over a guide-wheel 3, and through slots 4—4^a—4^b in a guide block 5, depending upon the width of the strip.

45 6 is a feed table over which the tickets or labels pass to the platen 7, which is embedded 50 in the present instance in the outer end of the

feed table. The feed table has longitudinal grooves 8 for the fingers 9 of a pawl 10, the fingers engaging notches *b*—*b* in the gummed label strip *a*, Fig. 7, and as the pawl reciprocates over the feed table it feeds one section of the label strip at a time to the position on the platen.

55 11 is a pressure-foot which is located above the table and is secured to the block 5 by a pin 12 on which is a spring 13 held by a nut 14, so that the pressure-foot can yield when necessary to accommodate tags of different thicknesses. At one side of the pawl 10 is a narrow pawl 15 which has a reduced end 16 arranged to engage the notches *c* in the strip of pin-tickets *d* or string-tickets *e*, Figs. 8 and 9.

60 At one side of the feed table is a plate 17 spaced sufficiently from the edge of the feed table to form a channel *x* for the passage of the prongs *d'* of the pin-ticket or the strings *e'* of the string-tickets.

65 In the upper edge of the plate 17 is a lip 18 which is located beyond the pawls so as to prevent the tickets lifting with the printing mechanism. The tickets, after being printed, are discharged from the end of the machine.

70 The pawls are mounted on a lever 19 pivoted at 20 to a fixed arm 21 secured to any fixed point on the machine. The lever 19 in turn is connected by a link 22 to the hand lever 23, which is pivoted at 24 to a bracket 25 on the frame of the machine and is held in its raised position by a spring which tends to yieldingly hold the lever in its raised position as shown in Fig. 1. On the outer end of the hand lever 23 is a handle 26 by which the lever is operated.

75 27 is a chase which is mounted in a chase-holder 28 having grooves 29 into which ribs 30 on the chase 27 slide. The chase is held in position by a latch 31 and the type 32 is held in the chase in the ordinary manner.

80 In order that the machine may print either with the lines of printing running parallel with the longitudinal line of the machine or at right angles thereto, the chase-holder is pivotally mounted in the head 33 of the lever 23. The chase-holder has a shank 34 which 85

extends through an opening in the head 33 and is attached in the present instance to the handle 26 by a screw which passes through the handle and into the shank 34. 35 is a locking pin arranged to enter either the hole 36 or the hole 37 in the chase-holder and is held in position by a spring 38.

39 is an inking-pad carried by a frame 40 which is mounted on the pivot 20 and connected by a link 41 to the head 33 on the operating lever 23, so that when the lever is depressed to make an impression on a tag the inking-pad is withdrawn, and when the lever is released the inking-pad assumes a position directly under the type, inking the surface thereof.

The operation is as follows:

If a gummed label strip is used, the same is mounted within the base and fed through the opening 2, passed around the wheel 3, through one of the slots 4, and under the presser-foot 11, where it is engaged by the pawl 10 and fed forward one label at a time by the feed mechanism; an impression is made, and the label strip passes out of the end of the machine.

When a pin-ticket or a string ticket is to be printed, then the ticket is fed through the slot 4^b, Fig. 3, which is open at one end, and the pin or string extends into the space α between the edge of the feed table and the plate 17. In this instance the pawl 15 enters the notches on one side of the tag strip only and feeds the strip forward into the printing position, the printing, in this instance, being at right angles to that of a gummed label, consequently the platen will have been adjusted.

In some instances, instead of mounting the chase holder on a pivot, the chase holder 28^a may have two ways, one at right angles to the other, so that the chase can be either located in one way or in the other way, which would be at right angles to the first-mentioned way, as shown in Figs. 10, 11 and 12.

We claim:—

1. The combination in a machine for printing tickets and labels, of a base; a feed table over which the tickets or labels are fed; a pawl engaging one strip of tickets; a narrow pawl for engaging one edge of another strip of tickets; and mechanism for printing the tickets or labels.

2. The combination in a machine for printing tickets and labels, of a base; a feed table over which the tickets or labels are fed; a wide pawl engaging one strip of tickets; a narrow pawl for engaging one edge of another strip of tickets, said feed table having a channel at one side for the passage of pins or strings attached to the tickets; and mechanism for printing the tickets or labels.

3. The combination in a machine for

printing tickets and labels, of a base; a feed table having two longitudinal grooves therein; a presser-foot mounted above the table; a reciprocating pawl having fingers extending into the grooves and arranged to enter notches at each side of the ticket or label; a narrow pawl at one side of the first-mentioned pawl and arranged to engage the notches on one side of a strip of tickets; a plate spaced from the feed table forming a space through which the pins or strings attached to the tickets pass as they are being fed forward; and mechanism for printing the tickets or labels.

4. The combination in mechanism for printing tickets or labels, of a base; a feed table; a platen at one end of the feed table; a guide block at the other end of the feed table, said guide block having slots through which the tickets or labels pass, said slots being of different widths and one of the slots being open at one side; a plate at one side of the feed table spaced therefrom to form a channel for the passage of pins or strings attached to the tickets; mechanism for feeding the tickets forward one at a time; and printing mechanism for making an impression on the tickets as they are fed to a position over the platen.

5. The combination in mechanism for printing tickets or labels, of a base; a feed table over which the strips of pin-tickets or labels are fed; means for feeding the tickets forward one at a time into printing position; a head; a chase-holder pivotally mounted in the head; a chase carried by the head, said chase-holder being adjustable in the head so as to print longitudinally or transversely of the tickets or labels.

6. The combination in a ticket or label printing machine, of a base; a feed table; means for feeding the strip tickets over the table into the printing machine; an arm; a head on the arm; a chase-holder pivotally mounted on the head; means for locking the chase-holder in either of its two positions; a chase carried by the head and arranged to receive the strip, said chase-holder being adjustable so as to print the tickets or labels either longitudinally or transversely thereof.

7. The combination in a ticket or label printing machine, of a base; a feed table over which a strip of tickets is fed; means for feeding the strip ticket forward one at a time; an arm; a head carried by the arm; a chase-holder pivotally mounted in the head and arranged to be turned in either of two positions; a spring-pressed pin for locking the chase-holder in either of its two positions; a type chase carried by the head; inking mechanism connected to the head; and feed mechanism actuated on depression of the lever.

8. The combination in a ticket and label printing machine, of means for feeding la-

5 belts or tickets to the printing position; movable means for carrying a chase; and a chase adjustably mounted on said movable means so that it can be adjusted in one of two positions, one position being at right angles to the other position.
